UNITED STATES PATENT OFFICE.

GUSTAV SCHUMACHER, OF CHICAGO, ILLINOIS.

DESIGN FOR A METAL-FRAMED ROCKING-CHAIR.

SPECIFICATION forming part of Design No. 35,681, dated February 4, 1902.

Application filed January 2, 1902. Serial No. 88,252. Term of patent 7 years.

To all whom it may concern:

Be it known that I, GUSTAV SCHUMACHER, a citizen of the United States, residing at Chicago, in the county of Cook and State of Illinois, have invented and produced a new and original Design for Metal-Framed Rocking-Chairs, of which the following is a specification, reference being had to the accompanying drawings, forming a part thereof.

Figure 1 is a front view of a rocking-chair, showing my new design. Fig. 2 is a side view of the same.

As shown in the drawings, the leading or material features of my design consist of a continuous framing of the back-supports A, which are carried over at the top to connect with each other, seat-supports B, legs C, and

rockers D, disposed or arranged as shown in Fig. 2, open scrollwork panels E in the back, with a plain panel F therebetween, and curved 20 arms G, extending from the back to the seat supports.

Having described my invention, what I claim as new, and desire to secure by Letters Patent, is—

The design for a metal-framed rocking-chair, as herein shown and described.

In testimony whereof I have signed my name to this specification in the presence of two subscribing witnesses.

GUSTAV SCHUMACHER.

Witnesses:

C. K. CHAMBERLAIN,
ANNIE S. PHILLIPS.
